UNITED STATES PATENT OFFICE.

WILLIAM LORD, OF NEW YORK, N. Y., ASSIGNOR TO HARTFORD RUBBER WORKS COMPANY, A CORPORATION OF CONNECTICUT.

LET-OFF OR WARP-TENSION DEVICE FOR LOOMS.

1,117,071.

Specification of Letters Patent.

Patented Nov. 10, 1914.

Application filed April 22, 1912. Serial No. 692,855.

To all whom it may concern:

Be it known that I, WILLIAM LORD, a citizen of the United States, residing in the city, county, and State of New York, have 5 invented certain new and useful Improvements in Let-Off or Warp-Tension Devices for Looms, of which the following is a full, clear, and exact disclosure.

The object of my invention is to provide 10 a let-off mechanism and tension device for looms which is mechanically controlled not by the tension of the warp but by the position of the whip-roll and which at the same time is very sensitive and efficient in securing 15 a uniform let-off of the warp-threads, thereby enabling the fabric to be woven with a uniform mesh and of a uniform width.

Briefly my invention comprises the employment of weighted levers which act upon 20 a movable bar termed a "whip-roll", over which the warp-threads pass from a warp-beam or spool. The rotation of the warp-beam is controlled through the medium of a friction clutch interposed in the mechanism 25 for rotating the warp-beam, said clutch being controlled by said levers.

For a detailed description of one form of 30 my invention, which I at present deem preferable, reference may be had to the following specification and the accompanying drawings forming a part thereof, in which:

Figure 1 is a side elevation of the warp-end of a loom showing my improved let-off device applied thereto; and Fig. 2 is an end 35 elevation of the same.

Referring to the drawings, the numeral 1 indicates the warp-beam or spool on which the warp-threads are wound. Said threads 2 pass thence over the movable whip-roll 3, 40 as indicated in Fig. 1, and thence under the binder bar as indicated at 4 by dotted lines. From this point the warp-threads then run to the heddles in the usual manner. The whip-roll 3 is fixed on suitable brackets 5 which are fixed on the transverse shaft 6, 45 carried in the grooved bearings 7. Upon one end of the shaft 6 is fixed a lever 8 carrying at its off-set upper end two adjustable weights 9 and 10. The opposite end of the 50 shaft 6 carries a downward off-set lever 11 which also carries an adjustable weight 12 at its outer end. These weights 9, 10 and 12 are what primarily produce the uniform tension upon the warp-threads.

55 The let-off of the warp is secured by the

following mechanism: The warp-beam or spool 1 carries the usual gears 13 fixed to the ends thereof. One of these gears is adapted to mesh with the small spur-gear 14 fixed to the end of a shaft 15 which is rotatably mounted in the bearing 16 fixed to the lower portion of the frame of the loom. The outer end of the shaft 15 carries a worm-gear 17. This engages a screw-gear 18' fixed to the end of a shaft 18, inclined somewhat to a horizontal line, and which is journaled in the bearing 19, attached to the lower portion of the frame of the loom. The upper end of the shaft 18 may have a hand-wheel 20 attached thereto for rotating the warp-beam 60 independently of its driving mechanism when necessary. Keyed to the shaft 18, and 65 slide longitudinally thereon, is one member 21 of a friction clutch having a grooved collar 22 engaging a yoke 23 carried on the lever 24. This lever is pivoted at its lower end to a stud 25 projecting from the frame of the loom. The upper end of the lever 24 is slotted, as indicated at 26, and engages a pin 27 projecting from the weighted lever 70 11. Mounted loosely on the shaft 18 is a second member 28 of the friction clutch which has fixed to it a bevel gear 29. This 75 bevel gear meshes with a bevel gear 30 carried on the transverse driving shaft 31, 80 which latter may be constantly driven in any suitable or well-known way.

It will now be seen that when the picks 85 advance the warp 2 the whip-roll 3 is depressed and raises the lever 11 and pin 27, 90 the lever 24 will be moved toward the right so as to cause the clutch members 21 and 28 to engage each other. Now supposing the gear 30 is turning in a clockwise direction, as indicated by the arrow in Fig. 1, the 95 shaft 18 will be rotated in an anti-clockwise direction as viewed from the end of the shaft having the hand-wheel 20, which will cause the screw-gear 17 and the spur-gear 14 to turn in an anti-clockwise direction, as 100 indicated by the arrow in Fig. 1. Consequently, the warp-beam will be turned in a clockwise direction, as indicated by the arrow, and the warp let off or advanced. Since this allows the whip roll to rise and 105 the weights to be lowered, the clutch members 21 and 22 will be disengaged and the rotation of the warp-beam will cease until the picks of the loom have again depressed the whip-roll. It will be obvious by rea- 110

son of the comparatively long distance between the fulcrum 6 of the lever 11 and the pin 27 that a very slight movement of the whip roll only is required to determine the frictional engagement or disengagement between the members 21 and 28 of the friction clutch, and since the let-off action is independent of the tension produced by the constant weights, the tension of the warp will be maintained constant. The levers 8 and 11 being arranged so that the weights 9 and 10 as regards the weights 12 are substantially at right angles to the shaft 6. The effect of the weights 9 and 10 will increase as they descend and compensate for any decrease of the weight 12 as it descends, thus making the tension upon the warp constant, although the weights move in arcs above and below the level of the shaft 6. In other words, the effective center of gravity of the combined weights is on a horizontal plane with the axis of the shaft 6. Owing to the nature of the friction clutch, the device is particularly free from the effect of the relative humidity and dryness of the atmosphere and the tension maintained the same in spite of variations in weather conditions. The tension of the warp being produced primarily by the weighted levers, or in other words, by force of gravity, there is no variation of this force and a complete warp may be run through the loom and woven into fabric without any adjustment whatever of the weights, and in fact, as a matter of practice, it has been found that a number of warps may be run through the loom without any adjustment of the weights or the let-off device whatever. In view of these advantages, my improved let-off device is particularly adapted for weaving canvas or duck to be used in the manufacture of pneumatic automobile tires in which the tension and crimp between the warp and the woof threads should be absolutely the same, in view of the fact that this fabric when so employed is usually cut on the bias. The uniform mesh produced by this let-off device also enables the reticular nature of the fabric to be constant and unvaried, thereby insuring a perfect and uniform penetration of the rubber compound between the threads of the warp and woof. This obviously reduces the tendency of friction to cause separation in spots between the rubber and fabric.

Having thus described this form of my invention, I do not wish to be understood as limited to the details of form and arrangement of parts herein set forth, for various changes may be made by those skilled in the art without departing from the spirit and scope of my invention.

What I claim and desire to protect by Letters Patent is:

1. In a let-off device for looms, the com-

bination of a warp-beam, driving mechanism therefor, a clutch in said driving mechanism, a lever for operating said clutch, a whip-roll, weighted levers supporting said whip-roll, and a pin and slot connection between one of said weighted levers and said clutch lever to give a transverse movement to said clutch lever to operate the clutch. 70

2. In a let-off device for looms, the combination of a warp-beam, driving mechanism therefor, a friction clutch in said driving mechanism, a lever for moving one member of said clutch, a whip-roll, weighted levers supporting said whip-roll, one of which acts directly on said clutch lever to 75 make said clutch operative or inoperative.

3. In a let-off device for looms, the combination of a warp-beam, intermittent driving mechanism therefor, a whip-roll, horizontally extending levers supporting said whip-roll, adjustable weights carried by said levers, and a controlling lever connecting directly between one of said levers and said driving mechanism for rendering the latter active or inactive. 85 90

4. In a let-off device for looms, the combination of a warp-beam, driving mechanism therefor, a whip-roll, weighted levers supporting said whip-roll at each end thereof, one of said levers being horizontally off-set above said roll and the other being horizontally off-set below said roll, and connecting means between the latter lever and said driving mechanism for rendering the latter active or inactive. 95 100

5. In a let-off for looms, the combination with a warp beam, driving mechanism therefor, a whip roll, weights for moving said whip roll, a lever controlled by the position of said whip roll, the outer end of said lever being much longer than the distance from its fulcrum to the axis of said roll, friction clutch for connecting and disconnecting said driving mechanism, and means connecting said clutch with a point adjacent the outer end of said lever for rendering the former active by a slight movement of the latter. 105 110

6. In a let-off for looms, the combination with a warp beam, driving mechanism therefor, a whip roll, weighted levers supporting said whip roll, said levers being relatively much longer than the distance from their fulcrums to the axis of said roll, a friction clutch for connecting and disconnecting said driving mechanism, and means connecting said clutch with a point adjacent the outer end of one of said levers for rendering the former active by a slight movement of the latter. 115 120 125

7. In a let-off for looms, the combination with a warp beam, driving mechanism therefor, a whip roll, a shaft about which said whip roll may oscillate, a relatively long weighted lever fixed on said shaft, connec- 130

tions between said shaft and said whip roll for oscillating the same, a friction clutch for rendering said driving mechanism operative or inoperative, and a connection between a 5 point adjacent the outer end of said lever and said clutch for rendering the latter active by a slight movement of the whip roll.

8. In a let-off for looms, the combination 10 with a warp beam, driving mechanism there- for, a whip roll, a shaft about which said whip roll may oscillate, a relatively long weighted lever fixed on said shaft, connec- tions between said shaft and said whip roll for oscillating the same, a friction clutch

for rendering said driving mechanism oper- 15 ative or inoperative, a connection between a point adjacent the outer end of said lever and said clutch for rendering the latter active by a slight movement of the whip roll, and a stationary binder bar about which 20 the warp passes after leaving the whip roll.

Signed in the city, county and State of New York, this 19th day of April, 1912.

WILLIAM LORD.
